AUTOMATIC CUTTING DEVICE.

Application filed November 13, 1925. Serial No. 68,839.

Our present invention relates to devices for cutting and winding web material, such as fabric which has passed through a rubberizing calender. It has for one object the automatic control of the cutting and winding mechanisms so that the cutting of the stock and the changing of the winding operation from one unit to another may take place without stoppage or slowing down of the rubberizing calender or other equivalent device. It has for another object the improvement of the cutting mechanism, particularly in the interests of simplicity and of reliability in operation. Other and further objects will appear from the following description and claims.

Referring to the drawings,

Fig. 1 is a side elevation of a cutting and winding apparatus constructed in accordance with our invention;

Fig. 2 is a detail thereof;

Fig. 3 is a front elevation of the knife operating mechanism, taken on line 3—3 of Fig. 1;

Fig. 4 is a side elevation thereof, partly broken away, drawn on a scale larger than that of Fig. 1;

Fig. 5 is a wiring diagram of the control device and the means for coordinating the different mechanisms so that they perform their operations in the desired sequence upon the actuation of a single control;

Fig. 6 is a diagrammatic side elevation illustrating of the setting of the invention in an installation for producing rubberized cord fabric;

Fig. 7 is a partial wiring diagram showing the initial energizing of the control circuits for the cutter;

Fig. 8 is a similar diagram showing the energizing of the cutter motor operating circuits;

Fig. 9 is a similar diagram showing the operation of the dynamic brake circuit for bringing the cutter motor to a stop; and

Fig. 10 is a view similar to Figs. 7 and 8, but showing the alteration in the circuits for operating the motor in the reverse direction, the control circuits being shown in dotted and the operating circuits in full lines.

In a previously filed application Serial No. 20,398, filed April 3, 1925, we have described a wind-up device somewhat similar to that

described herein. In that case, however, the cutting was done by hand and the calender was slowed down in order to give time for the performance of this operation. In the system shown in the present application the cutting operation has been so speeded up that slowing down of the calender is unnecessary. The mechanism to be described operates automatically to stop the travel of the web past the cutting point, to temporarily store that part of the web delivered by the calender during the duration of the cutting operation, and to restore the different parts of the system to the normal condition of equilibrium after cutting of the web has been completed.

The general arrangement of apparatus in the setting for which our invention has been particularly designed is shown diagrammatically in Fig. 6. In that figure the web of material is denoted by *m*. This material, which initially may be a woven fabric, an unconnected sheet of parallel cords, or other material, is, in the present embodiment, first fed through a rubber coating calender A where it receives a coat of rubber on both sides. It then passes through tension equalization rolls B and a weighing device C. D represents a take-up, tension, and controlling device which has various important functions in the operation of the apparatus. Passing over cooling rolls E the web *m* reaches the cutting mechanism F and finally duplicates winding devices G and G'.

The calender A is driven by a motor (not shown) which also, by chain connections 11, 12 and 13 (Fig. 6) drives the tension rolls B. The cooling rolls E may be driven by a chain connection 14 from a motor 15, or may run idly. In the former case a chain 16 connects them with a conveyor 17 which carries the web *m* to the cutting and winding devices. A third motor 18 (Fig. 1) drives, by suitable gear connections and chains 19, two shafts 20 and 20' which furnish the power for the two wind-up devices. Before describing the manner of control and coordination of the various devices the mechanical features of the cutting and winding devices will be considered.

As mentioned above the web *m* is carried to the cutting and winding devices by a belt conveyor 17. Positioned above this conveyor, and driven from the latter by a chain

connection 21, is a roll 22 which holds the web off the conveyor to allow the cut to be made without injury to the belt. The sprockets driving this roll, and the diameter of the 5 roll itself, are designed so that its surface speed is slightly less than the surface speed of the belt. This proportioning of the parts has a function useful in preventing wrinkling of the stock after the cut is made.

10 Slightly beyond the roll 22 is a guide or track 23 extending transversely of the conveyor to points well beyond the edges of the web *m*. A carriage 24 runs on this guideway by means of grooved rollers 25. A cutter 26 15 in the form of a circular disc is pivoted for rotation on this carriage, and has fixed to it a sprocket 27. Idle sprockets 28 are also journaled on the carriage, and direct around the sprocket a chain 29. This chain passes 20 around an idle sprocket 30 at one end of the guideway and at the other around a sprocket 31 on the shaft of a motor 32, being secured at each end, as at 33 and 34, to the carriage 24. As the motor 32 rotates in one direction or 25 the other, the carriage 24 will be moved rapidly from one end to the other of the guideway and the cutting disc simultaneously rotated at a high speed.

After passing the plane in which the cutting disc moves, the web *m* passes under an idle roll 35 which serves to keep it in proper position, and finally reaches the winding devices. The details of these winding devices are not material to the present invention, and 30 the general construction only will be described. A more complete mechanical description is found in our prior application Serial No. 20,398, filed April 3, 1925. The liners 36 are supplied on spools 37. After 35 passing under spreader bars 38 they go around rolls 39 and 40 to the wind-up rolls 41, mounted on and driven by an adjustable friction clutch from shafts 20 and 20'. The web *m*, instead of passing around these same 40 rolls on its way from belt 17 to the wind-up, passes around rolls 42 and 43, joining the liner on roll 40.

In order that the speed of the conveyor 17 shall be synchronized, at all times except 45 during the special operations described below, with the speed with which the web *m* is delivered by the calender, an automatic control is provided for the conveyor motor 15 operated by the floating roll 44 of the tensioning and controlling device D. For this purpose the roll 44 is connected with a chain 45 which passes over a sprocket 46 on the shaft of a rheostat 47 (Fig. 5), terminating in a counterbalancing weight 48. The rheostat 50 47 is included in series with the shunt field 49 of the conveyor motor 15. If this motor tends to run at a speed lower than that required to make the speed of belt 17 correspond with the speed with which the web *m* 55 is being delivered by the calender, the web

will accumulate between the calender and the conveyor, allowing the roll 44 to descend. This movement turns the rheostat 47 slightly in such a direction as to insert additional resistance in the field circuit of the motor, 70 whereupon the latter will increase its speed. A similar but inverse action will take place if the motor 15 tends to drive the conveyor at too high a speed. In practice it will be found that little or no motion of the rheostat 75 will occur during the operation of the device, the motors finding a condition of equilibrium and fluctuating only a very slight amount.

The cutting mechanism has been arranged so as to operate very quickly, avoiding any 80 necessity of slowing down or stopping the calender. The movement of the web past the cutter is temporarily arrested, the slack between that point and the calender being taken up by the device D. The entire manual control of the cutter and of the motion of the stock is centered in the two push buttons 50 and 50' (Fig. 5), these being used alternately. The electrical control devices will be considered in the sequence in which they operate. 85

Assuming that push button 50 is depressed, the first effect will be an opening of the circuit through the solenoid 51 of a contactor 52. This contactor, which in Fig. 5 is shown open or inactive on account of the open position 90 of main switch 53, will be raised or closed during the normal operation of the calender. In its closed position it short circuits that portion of the field rheostat 47 between the contact arm 54 and the terminal 55. The 100 effective portion of the rheostat during normal operation therefore lies between the contact arm and the second terminal 56. When the solenoid 51 is de-energized by the depression of push button 50 the short circuit between contact arm 54 and the terminal 55 is broken, throwing the entire rheostat into series with the shunt field 49. Since an increase of resistance in the field of a shunt motor increases the speed of the motor, the 105 motor 15 will speed up, increasing the speed of the wind-up conveyor 17. The calender runs throughout at a constant speed, and this acceleration of the wind-up diminishes the amount of slack in the take-up device D and 110 raises the floating roll 44. On account of the opening of the contactor 52 the rotation of the contact arm 54 by chain 45, while it takes place with variations in position of roll 44, produces no electrical effect. 115

When the roll 44 nears the top of its travel it strikes the arm of a limit switch 57, breaking the circuit through the solenoid 58 of a contactor 59 and thereby opening the circuit through the conveyor motor 15. The 120 wind-up conveyor thereupon comes to a stop. Since, as always, the calender motor is still running at a constant speed, slack will accumulate in the take-up D and the floating roll 125 will descend. The limit switch 57 is so ar- 130

ranged, in a manner to be described, as to remain open until the floating roll has reached the bottom of its travel, and in the period of descent of the roll the cutting operation takes place. Consideration of further operation of the motor 15 can therefore be deferred until the manner of actuation of the cutter has been described.

Starting, then, with the opening of the circuit through the contactor 59—the push button 50 being still held depressed by the operator—the following functions are performed by the control of cutter motor 32. As well as forming part of the circuit through the motor 15 the contactor 59 is part of the circuit through the solenoid 60 of a contactor 61, and the latter drops simultaneously with the stoppage of motor 15. The contactor 61 when closed by the opening of the circuit through its solenoid 60 allows current from one side of the line, here for convenience indicated as positive, to reach motor 32 and the controlling mechanism for it.

Tracing the path of the current from the positive side of the line (see Figs. 5 and 7) it passes first through the resistance 62 of a temperature control device of standard construction, through the contactor 63 thereof, through the now closed circuit between the upper contacts of the push button 50 (which, it will be remembered, is being held depressed by the operator), through a limit switch 64, and then divides, part passing through the solenoid 65 of a contactor 66 and part through the coil 67 of a contactor 68. The current finally passes through a ballast resistance 69 and back to the negative side of the line. This condition of the circuit is shown in Fig. 7, other parts and portions of the circuit being omitted for purposes of clearness.

The actions just described merely prepare the way for the circuit through the cutter motor 32. This latter circuit is shown separately in Fig. 8, it being understood that the current in the control circuits of Fig. 7 persists during the operation. Considering the operating circuits of Fig. 8 separately from the control circuits of Fig. 7, the current from the positive side of the line passes through the resistance 62 and through the armature of the contactor 68, which it will be recalled has been shifted to the left as viewed in the drawings by the energizing of its solenoid. It then passes through the armature 70 of motor 32, through the unenergized armature of a contactor 67', similar in construction to contactor 67, through the closed contactor 66, which was energized by the control current, through a ballast resistance 71, and back to the negative side of the line. The field coils 72 of the motor 32 are shunted across the line and are energized whenever the contactor 61 is closed. For convenience in referring to the reversing of motor 32 the path

of the current from positive to negative has been shown by arrows.

When current flows as indicated in Fig. 8 the motor 32 will turn, moving chain 29 and causing the carriage 24 to be moved across the path of the web *m*, with a consequent rotation of the cutter and severance of the web. When the carriage nears the limit of its travel a rail 73 (Fig. 3) borne by it strikes the actuating roll 74 of the limit switch 64. The actuation of the limit switch breaks the control circuit shown in Fig. 7 in the same way as if the operator had removed his hand from the push button 50 at exactly the right moment of time, and restores the motor operating circuit to the condition shown in Fig. 5. The operating circuit has been isolated in Fig. 9 to show more clearly the action which takes place. It will be apparent from Fig. 9 that the armature of the cutter motor 32 is short circuited through a resistance 75, while the field coils are still energized from the main line. This action, commonly referred to as dynamic braking, brings the motor 32, and consequently the cutter carriage 24, to an almost instantaneous though smooth stop.

Although the foregoing cutting operations have taken some space to describe, they in reality are completed in a fraction of a second. The calender still continues at its constant speed to turn out additional length of the web *m*, and this length continues to be taken up by the roll 44. Shortly after the completion of the cutting stroke this roll reaches an arm 76 which is connected by a linkage 77 with the limit switch 57 so as to close it when struck by the roll. That switch, which when opened by the upward travel of roll 44 stopped the conveyor motor by opening contactor 59, now by its closing starts the conveyor motor again, and also energizes the solenoid 60, breaking the circuit to the cutter motor. At any time shortly after the completion of the cutting operation the operator may remove his hand from button 50, and the conveyor motor, through the governing action of the floating roll 44 as previously described, seeks its proper speed and continues steadily until the next cut is to be made.

The next cut is brought about by the operator pressing the button 50', buttons 50 and 50' being used alternately. The action is exactly similar to that produced as above except that the contactors 66' and 68' are used instead of the corresponding ones 66 and 68, and that the current flows through the armature of the cutting motor in a reverse direction, causing reversal of the motor travel. This has been shown in Fig. 10, the control circuit being shown in dotted and the operating circuit in full lines.

While the specific electrical devices chosen have been described with some particularity in the interest of clearness, it should be un-

derstood that other connections or types of apparatus may be used as desired by the installing electrician. The apparatus is not restricted to winding up material delivered from a rubberizing calender, but may be used wherever a supply of continuous web material needs to be cut into lengths and wound up.

Having thus described our invention, we 10 claim:

1. An apparatus for cutting into lengths a continuously supplied web of material being furnished at a substantially constant speed, comprising means for delivering the material 15 from the cutting point, a floating roll constructed to take up slack between the supply and the delivery of the material and normally to control by its position the speed of the delivery, means for temporarily accelerating the delivery, means controlled by the approach of the floating roll to its upper limit for arresting the delivery, means similarly controlled for cutting the material while its motion is thus arrested, and means controlled 20 by the approach of the floating roll to its lower limit for restarting the delivery in normal operation.

2. An apparatus for cutting into lengths a continuously supplied web of material being furnished at a substantially constant speed, comprising means for delivering the material from the cutting point, a floating roll constructed to take up slack between the supply and the delivery of the material and 25 normally to control by its position the speed of the delivery, means for temporarily accelerating the delivery, means controlled by the approach of the floating roll to its upper limit for arresting the delivery, means similarly controlled for cutting the material while its motion is thus arrested, and means controlled 30

35

40

trolled by the approach of the floating roll to its lower limit for restarting the delivery in normal operation, and a single control for causing successive actuation of all of said 45 means.

3. In combination, means for continuously supplying a web of material, means for delivering the material for winding, cutting mechanism associated with the delivering means, means for taking up slack between the delivering means and the continuous supply adapted to equalize the feed of the continuous supply and the delivery means during the winding operation and having a maximum 50 capacity sufficient to accumulate the web during the operation of the cutter, means operative at the will of the operator to increase the speed of the delivery means to exhaust the slack in the take up means and means automatically responsive to the exhausting of the slack in the take up means to stop the delivery means and operate the cutter.

4. In combination, means for continuously supplying a web of material, means for delivering the material for winding, cutting mechanism associated with the delivering means, means for taking up slack between the delivering means and the continuous supply adapted to equalize the feed of the continuous supply and the delivery means during the winding operation and having a maximum capacity sufficient to accumulate the web during the operation of the cutter, means operative at the will of the operator to increase the speed of the delivery means to exhaust the slack in the take up means and means automatically actuated in sequence with the foregoing means for restarting the delivering means.
